UNITED STATES PATENT OFFICE.

ELMER E. WINGATE, OF WATERTOWN, MASSACHUSETTS.

CLOTHES-DRIER FOR LAUNDRIES.

942,692.

Specification of Letters Patent. Patented Dec. 7, 1909.

Application filed April 26, 1909. Serial No. 492,158.

To all whom it may concern:

Be it known that I, ELMER E. WINGATE, a citizen of the United States, and resident of Watertown, in the county of Middlesex and 5 State of Massachusetts, have invented an Improvement in Clothes-Driers for Laundries, of which the following description, in connection with the accompanying drawings, is a specification, like numerals on the 10 drawings representing like parts.

My invention is a rotary clothes drier having three principal objects, viz. the drying of a washing with extreme rapidity, effecting said drying without unduly mussing or 15 injuring the clothes, and effectually removing all the lint therefrom during the process of drying.

To this end my invention comprises a rotary drum having a screen-like periphery 20 for the free passage of air and moisture, divided transversely into a series of compartments, combined with means for delivering heated air transversely through the periphery of each compartment, and a housing for 25 collecting and removing the lint which is driven off from the clothes and out through the periphery of each compartment.

Further features of my invention, together with the constructional details and 30 advantages will be set forth more fully in the course of the following description, considered with reference to the accompanying drawings, in which I have shown a preferred embodiment of the invention.

35 In the drawings, Figure 1 is a horizontal longitudinal sectional view of the apparatus; Fig. 2 is a cross-sectional view thereof; and Fig. 3 is a fragmentary side elevation viewing Fig. 2 from the left.

40 Conveniently mounted to turn, as for instance upon journal bearings 1, 2, is a drum 3 of large capacity in accordance with the requirements of a usual laundry having a reticulated or screen-like periphery 4 and 45 separated by relatively heavy transverse partitions 5 into a series of compartments 6. The drum is further strengthened and braced by longitudinal paddles, ribs, or lifters 7 which serve the double purpose of 50 carrying the clothes up from the bottom to the top (whence they drop by gravity) and of strengthening the drum and constituting a portion of its carrying frame or framework. Preferably part of the lifters, as for instance 55 every other one, is short and the others long,

so as to carry the clothes to better advantage and tend to open them up and keep them from packing and rolling together as much as they would otherwise. This drum may be rotated by any suitable means, fast and 60 loose pulleys 8, 9 being herein shown as a convenient means for that purpose. This drum is mounted in a housing 10 provided with one or more doors 11, herein shown as slide doors of large capacity so as to permit 65 the clothes to be readily taken in and removed, and each compartment of the drum is similarly provided with a door 12, herein shown as hinged at 13.

At a convenient point, preferably at one 70 side and adjacent the lower portion of the drum, I provide a hot-air pipe 14 having a delivery spout 15 opening close to each compartment for delivering air through the peripheral screen thereof. This air is herein 75 shown as brought from the outside, as from a window or opening 16 and thence passed over steam coils 17 which heat it properly, and thence it is driven by a fan 18 under the desired force through the pipe 14 and 80 the spouts 15 into the compartments. As the screen of the drum rotates in the direction of the arrow, the clothes are carried around approximately halfway and thence permitted to fall in a loosened mass. During 85 their falling the hot air from the pipes 15 is forced under pressure through the screen and through these falling clothes, and this process continues rapidly so that all the moisture is driven from the clothes in a few 90 minutes. The moisture-laden air escapes through the screen opposite the pipes 15 and wherever there is no peripheral obstruction thereto, and carries with it the lint and other fibers which are loosened from the clothes 95 in the process of drying. I have found that this lint tends to collect in the top of the housing, and accordingly I have placed in the top, and preferably about opposite the hot-air pipe 14, an outlet pipe 19 which is 100 preferably connected to the housing by a pipe or elbow 20 opposite each compartment, as I have found that this arrangement is the most effectual. Also, if desired, walls 21, 105 22 are provided for preventing the escape of hot air from the pipe 14 around the drum instead of going through it.

For convenience of illustration, I have shown my apparatus as provided with four 110 compartments, but one of the advantages of

my construction is that it may readily be extended to accommodate any desired number of compartments. Each compartment is intended to hold an individual family washing, so that thereby they may be kept separate.

In use, the operator raises the door 11 and then lets down the door 12 of a given compartment, and dumps in the washing into that compartment. He then closes the door and starts the drum and fan. As the drum rotates, it carries with it on the left hand side the clothes, which are opened out and fall loosely as they reach the upper side of the drum. The blast of hot air from the adjacent spout 15 pours continually through the peripheral screen against the falling clothes, not only serving to open them out still farther but to dry them and carry away the moisture to the best advantage and with the utmost rapidity. The air, thus laden with moisture and also laden with the lint driven off from the loosened and falling clothes, escapes through those parts of the peripheral screen which are open, and at once escapes through the outlet pipes 19, 20. In a few minutes the dried and lint-free clothes are ready for removal. This is accomplished very readily simply by placing a basket in proper position, opening the door 12, whereupon the clothes are dropped into the basket and are removed. The separate compartments render impossible the contamination of one lot of clothes by the moisture and lint from the adjoining lot.

As already intimated, I do not intend to restrict my invention to the precise constructional details herein shown, as it is obvious that many changes in construction, proportion, and combination of parts may be resorted to within the spirit and scope of my invention.

Having described my invention, what I claim as new, and desire to secure by Letters Patent is:

1. A clothes drier, comprising a rotary drum divided transversely into individual compartments provided with means for continually lifting and dropping the clothes in said compartments, and having a screen-like periphery through which hot air may be driven, combined with means for introducing hot air transversely through said periphery into each compartment separately as the drum rotates, and means for collecting and withdrawing the lint and moisture-laden air after it has passed through the clothes.

2. A clothes drier, comprising a rotary drum having a peripheral screen through which hot air may be driven, lifters set radially lengthwise of said drum for carrying the clothes up from the bottom approximately to the top as the drum is rotated and permitting the clothes to open out and drop

by gravity, means for delivering hot air under pressure transversely through said peripheral screen including means for restricting said air-delivery to said transverse direction through the screen, for removing the moisture from the clothes as they fall, a housing inclosing said drum for collecting the moisture-laden air as it escapes from the drum, and outlet means for withdrawing the air and lint from said housing and continuously discharging the same from the apparatus.

3. A clothes drier, comprising a rotary drum having a peripheral screen through which hot air may be driven, lifters set radially lengthwise of said drum for carrying the clothes up from the bottom approximately to the top as the drum is rotated and permitting the clothes to open out and drop by gravity, air-confining means located adjacent the lower side of said drum for delivering hot air under pressure at a single restricted region transversely through said peripheral screen underneath said falling clothes for removing the moisture from the clothes as they fall, a housing inclosing said drum for collecting the moisture-laden air as it escapes from the drum, and outlet means for withdrawing the air and lint from said housing.

4. A clothes drier, comprising a rotary drum having a peripheral screen through which hot air may be driven, transverse partitions separating said drum into a series of individual compartments, lifters set radially lengthwise of said drum for carrying the clothes up from the bottom approximately to the top as the drum is rotated and permitting the clothes to open out and drop by gravity, means for delivering a separate jet of hot air transversely through said screen into each compartment for removing the moisture from the clothes as they fall, a housing inclosing said drum for collecting the moisture-laden air as it escapes from the drum, and outlet means for withdrawing the air and lint from said housing and discharging said air and lint from the apparatus.

5. A clothes drier, comprising a rotary drum having a screen periphery and divided into a series of distinct transverse compartments, lifting means therein for raising the clothes from the bottom to the top as the drum rotates for permitting the clothes to fall, a housing surrounding said drum for collecting and retaining the moisture driven from the clothes, hot-air delivering means within said housing, a nozzle adjacent the lower side of each compartment of said drum connected to said hot-air delivering means for delivering a jet of hot air through said screen into each compartment against the falling clothes, and outlet means including a pipe connection through the upper

portion of said housing opposite each compartment for withdrawing the moisture and lint from said housing as they are driven off from the clothes in the drum including
5 means for discharging said moisture and lint from the apparatus.

In testimony whereof, I have signed my

name to this specification, in the presence of two subscribing witnesses.

ELMER E. WINGATE.
